The Lowell Manufacturing Company of the same place

Letter Patent No. 474, Dated May 30, 1865

Design for a Carpet Pattern

The schedule referred to in three Letters Patent and making part of the same shall show it may concern:

Be it known that of Clemir J. Day of Lowell in the County of Middlesex and State of Massachusetts have originated and designed a new Pattern for carpets or other fabrics, of which the following is a full, clear and exact description, reference being had to the accompanying drawings, making part of this specification.

A. A. are two frames running irregular through the design.

B. C. and D. are three palm leaves resting between the frames A. A. The rest of the space between said frames are occupied by sprig work.

E. E. E. E. are parts of a large star and when matched will run at right angles with frame A. A. The particular form of said star is shown in the drawing.

F. F. are two halves of a leaf.

The colors employed for the different portions of the design may be varied to suit the taste and wish of the manufacturer.

Claim:

What I claim as my invention and desire to secure
by Letters Patent is the Design or Pattern for carpets or other fabrics herein set forth.
